OPERATING MEANS FOR HAND TOOLS
ADAPTED FOR USE IN RELATIVELY IN-
ACCESSIBLE OR CRAMPED LOCATIONS

Angelo Barbagelata, Matawan, N. J.

Application December 12, 1945, Serial No. 634,466

5 Claims. (Cl. 81—177)

1

The invention relates to hand tools and more particularly to means for manually operating the same.

The object of the invention is to provide an operating means of simple and sturdy construction which is adapted to serve with maximum efficiency in the hands of an operator for its intended purposes.

The invention contemplates further the provision of a novel hand tool particularly adapted for use in more or less inaccessible locations or in places where continuous rotative operation of the tool is impossible.

A still further object of the invention is to provide a hand tool of the indicated type which may be readily converted into a double or T wrench handle at the will of the operator.

Other more specific objects will appear from the description hereinafter, and the features of novelty will be pointed out in the claims.

In the accompanying drawing which illustrates an example of the invention without defining its limits,

Fig. 1 is a plan view of the novel operating means,

Fig. 2 is an elevation of the novel operating means combined with a predetermined tool, and

Fig. 3 is a fragmentary sectional view of the novel operating means.

As shown in the drawing, the novel operating means comprises a member having a circular body 5 including an internal chamber 6 and an annular flange 7 surrounding the chamber 6 and projecting inwardly relatively thereto as shown in Fig. 3. The flange 7 is provided at spaced intervals with open-ended notches 8 located in pairs in diametrically-opposed relation and extending downwardly into the upper portion of the body 5 as illustrated in Fig. 3.

The body 5 includes a downward extension 9 which is continued in the form of a stem 10 constituting part of the wrench or other tool with which the novel operating means is combined. A bearing member or head 11 is rotatably mounted in the chamber 6 by means of a rod 11—a which extends rotatably through an axial passage 12 and is connected by screw threads 15 with a sleeve 13 rotatable within an axial bore 14. The head 11 preferably is provided with a centering recess 11—b for centering the tool in a lathe, drill press, or other machine and, in addition, includes a transverse opening, one end of which flares outwardly as indicated at 17. A handle 18 in the form of a cylindrical rod is slidably mounted in the opening and is provided with annular grooves

19 and 20 located in spaced relation to each other upon the outer surface of the handle 18. The member 11 further may be provided with a detent for cooperation with the notches 19 and 20 to position the handle 18 in the member 11 as will be more fully described hereinafter. In the illustrated example, the detent comprises a spherical ball 21 resiliently urged toward the handle 18 by means of a spring 22 mounted in a cavity 23 formed in the member 11 for this purpose. In the illustrated construction, the chamber 6 is provided with a bottom comprising an annular concave channel 24 surrounding a portion providing a bearing surface upon which the member or head 11 rotatively rests.

The channel 24 provides space to enable the handle 18 to be shifted to the inclined position illustrated in Fig. 3 and thereby provides for the adjustment of said handle into and out of successive notches 8 of the body 5.

In practice, the handle projects diametrically outward from the body 5 through one of the notches 8 and extends diametrically through the member 11 with its end located in a diametrically-opposed notch 8 and thereby provides a single handle to be used as a lever for rotatively actuating the tool of which the operating means constitutes a part. If desired or found necessary, the handle 18 may extend diametrically through the head 11 and through diametrically-opposed notches 8 so as to project in opposite directions beyond the operating means as shown in Figs. 1 and 2 to thereby constitute a double handle. In the event that complete rotation of the tool on its axis by the handle 18 is impossible because of intervening obstructions, the handle may be withdrawn in the direction of its axis a sufficient distance to enable it to be elevated to the inclined position shown in Fig. 3 and then shifted into a succeeding notch 8 by rotating the member or head 11 on its axis until the handle 18 registers with said succeeding notch 8. The handle may then be depressed and again manipulated to rotate the tool through another step. This procedure is repeated to bring about a step by step rotation of the tool throughout the period required to complete the operation being performed thereby. The same result may be obtained by simply positioning the handle in one notch 8 and omitting axial adjustment of said handle to shift it into diagrammatically-opposed notches 8. The adjustment of the handle 18 to its inclined position to enable said handle to be shifted into successive notches 8 is made possible by the concave channel 24 and the elongated slots

17 formed by the flaring opposite ends of the opening as is clearly shown in Fig. 3.

With the novel operating means, it is easy to convert the tool, such as a wrench of which the operating means forms a part, into a double or T wrench handle by simply shifting the handle relatively to the member 11 until it extends diametrically in opposite directions from said member as shown in Figs. 1 and 2, for instance, when the detent 21 engages the groove 20. When the rod 18 is in position to constitute a single handle, it is maintained in this position by the engagement of the detent 21 with the groove 19.

The novel operating means, when combined with a tool, enables the tool to be used in confined spaces or in more or less inaccessible places as will be apparent. At the same time, by merely shifting the position of the rod 18 in the member 11 and locating it in two diametrically-opposed notches 8, the tool with which the operating means is combined becomes an efficient double or T wrench handle or other implement.

The novel operating means may be combined with existing tools by welding or otherwise connecting the stem of said operating means to a shank of said tools.

Although the present invention has been described in conjunction with a preferred embodiment, it is to be understood that modifications and variations may be resorted to without departing from the spirit and scope of the invention, as those skilled in the art will readily understand. Such variations and modifications are considered to be within the purview and scope of the claims.

I claim:

1. Tool operating means comprising a member having an axial stem provided with an axial passage and a continuing axial bore, said passage having a smaller diameter than said bore to define a shoulder therebetween, a cylindrical body located at one end of said stem and including an internal chamber having a bottom consisting of a bearing surface and an annular concave channel surrounding the same, an annular flange surrounding said internal chamber and provided with spaced open-ended notches located in pairs in diametrically opposed relation to each other, a head in said chamber rotatably supported on said bearing surface and having a transverse opening one end of which flares outwardly, a rod extending from said head through said axial passage and terminating in said axial bore, a sleeve fixed on said rod in said axial bore and having an outside diameter which is larger than the diameter of said passage, said sleeve engaging said shoulder to prevent axial movement of said head, said head, rod and sleeve being rotatable as a unit in said stem, a handle rod slidably mounted in said transverse opening of said head and provided with spaced circumferential surface grooves, said rod being adjustable angularly relatively to said head for shifting into successive notches to constitute a handle whereby said member is rotatably actuated in intermittent steps, and a resilient detent cooperating with said surface grooves to yieldingly maintain said handle rod in operative position on said head.

2. Tool operating means comprising a member having an axial stem provided with an axial passage and a continuing axial bore, said passage having a smaller diameter than said bore to define a shoulder therebetween, a cylindrical body located at one end of said stem and including

an internal chamber having a bottom consisting of a bearing surface and an annular concave channel surrounding the same, an annular flange surrounding said internal chamber and provided with spaced open-ended notches located in pairs in diametrically opposed relation to each other, a head in said chamber rotatably supported on said bearing surface and having a transverse opening one end of which flares outwardly, a rod extending from said head through said axial passage and terminating in said axial bore, a sleeve fixed on said rod in said axial bore and having an outside diameter which is larger than the diameter of said passage, said sleeve

engaging said shoulder to prevent axial movement of said head, said head, rod and sleeve being rotatable as a unit in said stem, a handle rod slidably mounted in said transverse opening of said head and adjustable angularly relatively to said head for shifting into successive notches to constitute a handle whereby said member is rotatably actuated in intermittent steps, and cooperative means on said handle rod and head whereby said handle rod is movably maintained in operative position on said head.

3. Tool operating means comprising a member having an axial stem provided with an axial passage and a continuing axial bore, said passage having a smaller diameter than said bore to define a shoulder therebetween, a cylindrical body located at one end of said stem and including an internal chamber having a bottom consisting of a bearing surface and an annular concave channel surrounding the same, an annular flange surrounding said internal chamber and provided with spaced open-ended notches located in pairs in diametrically opposed relation to each other, a head in said chamber rotatably supported on said bearing surface and having a transverse opening one end of which flares outwardly, a rod extending from said head through said axial passage and terminating in said axial bore, a sleeve fixed on said rod in said axial bore and having an outside diameter which is larger than the diameter of said passage, said sleeve engaging said shoulder to prevent axial movement of said head, said head, rod and sleeve being rotatable as a unit in said stem, a handle rod slidably mounted in said transverse opening of said head, and said handle rod being adjustable angularly relatively to said head for shifting into different notches to constitute a handle whereby said member is rotatably actuated in intermittent steps.

4. The combination of a tool operating member, a body located at one end thereof, an annular flange on said body provided with spaced, open-ended notches located in pairs in diametrically opposed relation to each other, a head rotatably combined with said body and having a transverse opening one end of which flares outwardly, a handle rod slidably mounted in said transverse opening and adjustable angularly relatively thereto for shifting into different notches to constitute a handle whereby said member is rotatably actuated at will, an extension on said head and rotatable in said body with the head, and means on said extension engaging said body to prevent axial movement of the head while said handle is being adjusted and shifted.

5. The combination of a tool operating member, an annular flange located at one end thereof and provided with spaced, open-ended notches located in pairs in diametrically opposed relation to each other, a head mounted at said one end

of said member for rotation relatively to said annular flange and having a transverse opening one end of which flares outwardly, a handle rod slidably associated with said head in said opening and angularly adjustable relatively thereto for adjustment into different notches to thereby couple said annular flange and head together, said handle rod being longitudinally adjustable to extend in one direction radially outward from said head and flange to constitute a single handle or to extend radially outward in an opposite direction to constitute a double handle, said handle rod in either position serving to rotatably actuate said member at will, and stop means carried by said head in engagement with the member to prevent movement of the head axially relatively thereto while said handle is being adjusted and manipulated.
